UNITED STATES PATENT OFFICE.

JAMES LOCKHART JARDINE, OF PENICUIK, SCOTLAND.

PROCESS OF PREPARING TEXTILE MATERIALS FOR BLEACHING.

1,143,543.

Specification of Letters Patent. Patented June 15, 1915.

No Drawing.

Application filed February 3, 1915. Serial No. 5,922.

To all whom it may concern:

Be it known that I, JAMES LOCKHART JARDINE, a subject of the King of Great Britain and Ireland, and a resident of Penicuik, in the county of Mid. Lothian, Scotland, have invented a certain new and useful Process of Preparing Textile Materials for Bleaching, of which the following is the specification.

10 The invention consists in substituting a single process for the alternate alkaline (bowking) and acid (souring) treatments, as used in the preparation of vegetable textile fibers for bleaching. I have discovered that the non-cellulose or incrusting constituents, which these chemical treatments remove, can be resolved and rendered soluble by the use of a solution of a bisulfite of a base (such as magnesium or sodium) 15 which yields a soluble sulfite. When using this bisulfite solution, the liberated SO₂ must be fully and completely removed so as to prevent the undue preponderance of acid in the solution, otherwise tendering of the 20 fibers would occur due to the formation of hydrocellulose. Further if the freed SO₂ be retained, reversals in the chemical action may occur with the precipitation of organic substances of powerful reducing properties. 25 The digestion is carried out in a closed vessel with acid proof lining under pressure, and heated preferably by means of coils or a jacket, or it may be heated by the application of direct steam, and the temperature and percentage strength of the 30 solution are varied to suit the material being treated, or the degree to which it is desired to be bleached, but in all cases it is essential for reasons given above to provide 35 a free outlet for the removal of the gaseous emanations, and this at the same time insures the uniform penetration of the liquor.

Resolution conducted under the above 40 conditions effectively removes the lignified 45 incrustations as well as the pectose and gummy ingredients, and as there is no tendency toward mercerization, the structural formation of the fibers or filaments are not much altered, and their strength is not unduly impaired. So mild is the action and yet so complete is the resolution that the 50 process can be carried out in one operation, to the extent necessary for easy bleaching of even jute and hemp.

55 The percentage composition of a suitable

bisulfite liquor, (i. e. the proportion of base and available or free SO₂) is to a certain extent dependent upon the period of time and the temperature of cooking—that is to say the stronger the liquor the shorter the time 60 at a given temperature, and vice versa, the effect being further modified by variation in temperature. The component percentages of base and available SO₂ are also varied to suit the nature of the fiber being treated according to its chemical characteristics (pectic or lignin) and its physical condition (simple fibers or filaments or thick woven textures).

65 In all cases, as already stated, it is however essential to provide for the free escape of the SO₂ gas which is liberated in the heating or digestion. If this is not provided for, the free acid will affect the fiber, forming hydrocellulose, and as this product 70 is of a friable nature, the strength of the fiber or fabric is destroyed, or the presence of the excess acid may cause a reversal in the action, resulting in the deposition of an aldehyde which renders the fiber difficult to 75 bleach. The lignified incrustations of the fibers are readily dissolved by the action of the SO₂, which on being used up in this way, or liberated as gas, frees the base 80 which then attacks the pectic and gummy 85 substances, resolving them, and thus the joint result is the removal of the materials which prevent bleaching. As neither the acid nor alkaline action of the bisulfite under the specified conditions is drastic, coupled with the fact that they throughout the 90 process coact, the incrusting ingredients are removed without risk of the cellulose being injured, and further, as there is no tendency toward mercerization, the structural formation of the fibers or filaments, is not materially altered, consequently their weaving 95 properties or tensile strength is not unduly impaired.

100 The incrusting ingredients combined or associated with all the bast or equivalent fibers are of lignin and pectic nature with admixtures of gums and waxes, and to get full bleaching with the use of a minimum percentage of the hypochlorite or other 105 bleaching agent, these must be more or less completely removed. Therefore SO₂ must be provided in sufficient quantity to sulfonate or dissolve the lignin, but as its exposure to the action of this acid is to a cer- 110

2
tain extent dependent on the removal of the other incrustants (and for the reasons already given a strong acid or too high a temperature must not be applied), the process must proceed slowly and concurrently with the pectic removal which requires the action of the alkaline base. If the fibrous substance is pronouncedly lignified as is the case with jute, a liquor with a larger percentage of free or available SO_2 must be provided than need be applied for say flax or hemp, where the pectic substances preponderate. So that when dealing with flax and hemp and like substances in which the pectic ingredients preponderate over those of lignin characteristics, it is not necessary to provide in the liquor when a sodium base is used, the full bisulfite proportions of SO_2 . An acid sulfite will be quite suitable provided it contains, as far as the vegetable tissue is concerned, an excess of free or available SO_2 , so insuring that all the lignin which is separated will at once be dissolved, the surplus escaping by the exhaust.

25 The continual relief of steam and the gaseous emanations, besides attaining the main chemical purpose as has already been described, also provides for the removal of any of the volatile waxes, and liberates air, so insuring uniform liquor penetration. Care must be taken that all the fibers are always completely immersed, as otherwise oxidation or burning will result.

Having made clear how the bisulfite solution acts, I now give details of methods applied to jute and hemp.

The examples of the digestions as hereafter given were done in a small experimental boiler lead lined and heated externally by gas.

45 Jute as raw fiber, or in the form of Hessian cloth, freed from the oils with which it has been impregnated to facilitate spinning, is placed in the digester, and covered by a solution giving the following analysis

Total SO_2 -----	3.5%
Available or free-----	2.1%

Combined-----	1.4%

50 made from a magnesium base. One gallon of this liquor is used for 1½ lbs. of cloth. The lid being bolted down, heating is commenced, and the full temperature of 280° F. is reached in four to five hours. Throughout all the cooking process a free escape to atmosphere is provided by the use of a small outlet pipe. During the initial stages of the heating this is kept full open to quickly remove the gasified SO_2 , but thereafter, as the rate of gas liberation is slower, the outlet may be partially closed; but the aperture must always be large enough to prevent the development of "false pressure" 60 in excess of that equivalent to the tempera-

ture and owing to gas accumulation. Thus the pressure will always be in accordance with the saturated steam equivalent of the temperature. As steam escapes with the gases, concentration of the liquor takes place, and water must be added from time to time to keep the cloth covered. I find that by maintaining this temperature for twenty hours the incrusting matters are so thoroughly removed that a white color can be easily obtained by the use of a relatively small percentage of a hypochlorite bleaching liquor. The residual liquor in the digester contains a fairly large percentage of MgSO_4 , but this salt must be present in excess as it provides the carrier for the free or available SO_2 .

Woven hemp, treated under similar conditions as to time and temperature with a bisulfite solution made from a magnesium base and containing the following percentages of SO_2

Total -----	3.2
Available or free-----	1.7
Combined-----	1.5

rials for bleaching in a single operation, which comprises treating the same with a solution of magnesium bisulfite, under pressure, at a temperature above the boiling point of water, but below that and for a period of time less than that at which the structural formation of the textile material would be destroyed, or the textile material reduced to a pulp or the fibers materially weakened, and removing substantially all the liberated sulfur dioxid during the treating step, whereby at first the acid salts in the liquor act upon the lignin, in said textile material and thereafter the base in the liquor acts upon the pectic principles of the textile material, but the physical structure of the material is not injured.

3. In the process of treating raw textile materials, to prepare the same for bleaching, the step of subjecting the same to the action of a solution of magnesium bisulfite of such a strength and at such a temperature, above the boiling point of water, as to avoid the formation of material amounts of hydrocellulose, and continuing said treatment for about 20 hours, while substantially continuously allowing the escape of sulfur dioxid, sufficiently to avoid the development of a pressure materially exceeding the steam pressure equivalent to the temperature employed, and discontinuing said treatment be-

fore the physical structure of the textile material is materially altered.

4. A process of preparing jute and similar textile materials for bleaching, consisting in treating the textile material, in a digester with a solution from a magnesium base containing:

Total SO ₂	3.5%	40
Available or free SO ₂	2.1%	
Combined SO ₂	1.4%	

one gallon of this liquor being used for each $1\frac{1}{2}$ lbs. of the textile material, and maintaining a temperature of about 280° F. for about twenty hours, while allowing the escape of sufficient SO₂ to prevent development of pressure in excess of the steam pressure equivalent to said temperature and adding water during the operation, in amount sufficient to make up for the loss produced by steam escaping with the gases, as described.

In testimony whereof I have signed my name to this specification, in the presence of two subscribing witnesses.

JAMES LOCKHART JARDINE.

Witnesses:

JAMES WILSON WRIGHT,
JOHN ROBERTSON.
